UNITED STATES PATENT OFFICE.

JOE SOLONY, OF DETROIT, MICHIGAN.

DESIGN FOR A RATTLE.

43,833.

Specification for Design.

Patented Apr. 8, 1913.

Application filed January 9, 1913. Serial No. 741,097. Term of patent 3½ years.

To all whom it may concern:

Be it known that I, JOE SOLONY, a subject of the Emperor of Austria-Hungary, residing at Detroit, county of Wayne, and State of Michigan, have invented a certain new, original, and ornamental Design for Rattles, of which the following is the specification, reference being had to the accompanying drawing, forming a part thereof.

The figure is a perspective view of a rattle, illustrating my new design.

I claim:—

The ornamental design for a rattle, as shown.

JOE SOLONY.

Witnesses:

THOMAS PRETOR,
STEVE PLOUF.
